(57) **CLAIM**

The ornamental design for a loudspeaker, as shown and described.

DESCRIPTION

FIG. 1 is a top perspective view of a loudspeaker showing our new design;

FIG. 2 is a front elevational view thereof;

FIG. 3 is a rotated elevational view thereof, shown rotated approximately 120 degrees from the view as shown in FIG. 2; and,

FIG. 4 is a top plan view thereof.

The broken line showings form no part of the claimed design.

1 Claim, 4 Drawing Sheets---
